INVENTOR:

Florence D. Roberts,
Russell M. Everett,
ATTORNEY.

UNITED STATES PATENT OFFICE.

FLORENCE D. ROBERTS, OF MONTCLAIR, NEW JERSEY, ASSIGNOR TO WELDON ROBERTS RUBBER COMPANY, A CORPORATION OF NEW JERSEY.

ERASER-BRUSH.

1,161,250.

Specification of Letters Patent. Patented Nov. 23, 1915.

Application filed September 12, 1913. Serial No. 789,426.

To all whom it may concern:

Be it known that I, FLORENCE D. ROBERTS, a citizen of the United States, and a resident of Montclair, in the county of Essex and 5 State of New Jersey, have invented certain Improvements in Eraser-Brushes, of which the following is a specification.

The objects of this invention are to provide an eraser brush adapted to be removably affixed to an eraser of ordinary construction; to enable the brush to be removed at pleasure and the eraser used without it; to employ a frictional engagement of the brush attaching means with the eraser, so that it is 10 readily applied or removed; to take advantage of the resiliency of the eraser in using the brush; to secure a simple and compact construction, with few parts, not liable to get out of order, and to obtain other advantages and results as may be brought out 15 in the following specification.

Referring to the accompanying drawings, in which like numerals of reference indicate the same parts throughout the several views, 20 Figure 1 is a side view of an ordinary circular eraser with my improved brush applied thereto; Fig. 2 is a sectional view on line A—A Fig. 1; Fig. 3 is a sectional view on line B—B of Fig. 1; Fig. 4 is a side view 25 of a brush alone, showing the brush proper at right angles to the attaching means; Fig. 30 5 is a view similar to Fig. 1, showing a modified form of attaching means for the brush; Fig. 6 is a sectional view on line C—C Fig. 35 1, and Fig. 7 is a similar sectional view illustrating a still further modification of attaching means.

In the specific embodiment of the invention illustrated in said drawings, the reference numeral 1 indicates an ordinary "circular" eraser to which I have shown my improved brush applied, but it is to be understood that my invention is equally applicable to other forms of erasers, and I do not wish 40 to restrict myself to any particular style. The eraser brush comprises attaching means and a brush proper carried thereby, said brush having a sweeping portion of any suitable material, although I have shown 45 50 bristles for illustration.

In the preferred construction, shown in Figs. 1, 2 and 3, the attaching means comprises a single piece of sheet metal doubled as at 2 to provide a pair of spaced jaws 3, 55 3 adapted to grip between themselves a mar-

ginal portion of the eraser 1. These jaws 3, 3 are bent at their edges away from the eraser to lie flatwise together, as at 4, 4 and the contacting portions are preferably of sufficient size to receive an eyelet 5 which is 60 passed through registering apertures and the two contacting portions 4, 4 of the sheet metal thereby clamped together. From these contacting portions 4, 4 extend ears 6, 6 lying flatwise together in the planes of the 65 portions 4, 4 and preferably projecting therefrom adjacent to the gripping jaws 3, 3, said ears being integrally joined at their outer ends at the line of doubling or folding 2. Furthermore, said ears provide between 70 themselves a socket 7 to receive a stem 8 of the brush proper, said stem being gripped and held in fixed relation to the ears 6, 6 when the eyelet is riveted into place.

It will be obvious that the direction in 75 which the ears 6, 6 extend from the contacting portions 4, 4 of the attaching means may be varied to suit the taste or desire of those making the article, without departing from the spirit or scope of the invention, and that 80 to vary the direction of the ears will result in supporting the brush at a corresponding deviation from a radial line of the eraser. For instance, in Fig. 4 I have shown ears 16, 85 projecting oppositely from the jaws 13, so that the brush proper lies at right angles to its position as shown in Fig. 1 or tangential to an eraser to which it may be applied.

The brush proper I have shown in Figs. 1 to 4 inclusive consisting of a tuft of bristles 90 seated in the flattened and enlarged end 10 of a tubular holder or ferrule the other end of which is reduced to form the stem 8 which enters the socket 7. Obviously any other suitable and equivalent construction could be 95 employed, however.

In Figs. 5 and 6 a brush proper is shown applied to an eraser 1 by attaching means comprising a U-shaped clip 11 with jaws 23, 23 adapted to grip the eraser, and apertured at its bottom, as at 12, to receive a reduced stem 28 of a ferrule whose bristle-holding portion 20 provides a shoulder 14 outside of the aperture to prevent inward displacement. After the stem is inserted in the aperture 12, its inner end is spread to retain the ferrule firmly in place, and solder may be applied to the joint, as well, if desired. In this form of the invention, I have shown the jaws 23, 23 adapted to project 100 105 110

under the side plates 15, 15 of the eraser, but obviously they could terminate short of said side plates 15, 15, if desired, as the jaws 3, 3 are shown in Figs. 1 and 2, or said jaws 3, 3 5 could be extended if desired like those in Figs. 5, 6 and 7. Or, in any pair of jaws, one could be long enough to enter beneath one side plate of an eraser, while the other jaw was too short to reach the other side 10 plate.

Fig. 7 illustrates a modification of the construction shown in Figs. 5 and 6, the ferrule being dispensed with and the bristles inserted directly into the aperture 15 22 of the clip 21 to secure a cheaper construction. Under some conditions, this 20 change might also be made in the construction shown in Figs. 1-4, and the bristles inserted directly into the socket between the ears 6, 6.

Many other modifications of construction can be made without departing from the spirit and scope of the invention, and I do not wish to be understood as restricting 25 myself except as required by the following claims when construed in the light of the prior art. By my invention the brush is attached to the eraser so that in using said brush by the eraser as a handle the resiliency of the eraser is imparted to the brush, and thus a softness of pressure in brushing 30 is secured which guards against any possible injury or harshness. It will be understood that in the class of erasers to which this invention relates the eraser is grasped by the finger and thumb pressing upon opposite sides of it against the two plates 15, 15, and thus by the attachment of the brush as set forth herein the resiliency of the exposed 35 peripheral margin of the rubber is secured in the use of the brush. Furthermore such resiliency may be secured in a varying degree, according to whether the brush is attached as in Fig. 1, with a single jaw 23 underlying 40 one of the plates 15 or with both jaws entering beneath said plates. Obviously in all these cases some resiliency is obtained, and the amount best adapted to the work to be done will determine which construction 45 shall be used.

Having thus described the invention what I claim is:

1. The combination with an eraser comprising a rubber disk with central plates 55 at opposite sides thereof of smaller diameter than said rubber and affording a grasping portion, of a brush attached to the edge of said rubber disk outside the metal side plates, whereby advantage is taken of the

resiliency of the rubber in using the brush 60 when the eraser is grasped by its side plates.

2. The combination with an eraser comprising a rubber disk with central plates at opposite sides thereof of smaller diameter than said rubber and affording a grasping 65 portion, of attaching means having arms engaging the rubber disk outside said side plates and conforming between said arms to the edge of said rubber disk and fitting thereagainst to prevent swinging in the 70 plane of the eraser, and a brush carried by said attaching means, whereby advantage is taken of the resiliency of the rubber in using the brush when the eraser is grasped by its side plates. 75

3. The combination with an eraser comprising a rubber disk with central plates at opposite sides thereof of smaller diameter than said rubber and affording a grasping 80 portion, of attaching means having arms frictionally engaging the rubber disk outside said side plates, said arms being extended circumferentially of the rubber disk, and a brush carried by said attaching means, whereby advantage is taken of the 85 resiliency of the rubber in using the brush when the eraser is grasped by its side plates.

4. The combination with an eraser comprising a rubber disk with plates at opposite sides thereof of smaller diameter than said rubber, of attaching means comprising a piece of sheet material doubled to form a socket at the line of doubling and jaws at the same side of said line of doubling as 90 said socket, means clamping the doubled portions together between said socket and jaws, and a brush mounted in said socket. 95

5. The combination with an eraser comprising a rubber disk with plates at opposite sides thereof of smaller diameter than said rubber, of attaching means having arms on opposite sides of the rubber disk one of them entering at its extremity between the rubber disk and one of its side 100 plates. 105

6. The combination with an eraser comprising a rubber disk with plates at opposite sides thereof of smaller diameter than said rubber, of attaching means having resilient arms gripping the rubber disk between themselves and projecting at their extremities beneath the side plates. 110
